SKULL FOR FUR NECKPIECES

Filed Nov. 6, 1930

CHARLES ABEL HOSIER
By Frederick C. Bromley
Attorney.

UNITED STATES PATENT OFFICE

CHARLES ABEL HOSIER, OF TORONTO, ONTARIO, CANADA

SKULL FOR FUR NECKPIECES

Application filed November 6, 1930, Serial No. 493,754, and in Canada March 10, 1930.

The invention relates to improvements in "skulls for fur neckpieces" as described in the present specification and shown in the accompanying drawings which form part of the same.

5 In the manufacture of such neckpieces, it is customary to fit a "skull" in the head of the animal in order to give it the proper shape and to also provide a support for attaching the lower jaw-piece by which the fur is fastened about the neck of the wearer.

10 Hitherto these skulls have been composed of a moulded rubber or fibre form to which is attached an upper jaw plate. A rubber skull has been found objectionable in that not only is it unduly heavy but also, owing to its pliancy, it too readily yields when the jaws are being opened, thus making the jaws 15 awkward to use. A fibre skull also becomes pliant when blocking the damped skin 20 upon the skull.

The present invention therefore has the object to provide an efficient and serviceable skull that will not have this detrimental pliancy, and that will be economical to manufacture and easy to assemble.

25 Referring to the accompanying drawings, Figure 1 is a perspective view of the skull together with the upper jaw plate.

30 Figure 2 is a side elevation of the skull and jaw plate depicting the lower spring jaw attached thereto.

Figure 3 is a plan view of the underside of the skull.

35 Figure 4 is a perspective view of the upper jaw plate viewed from its underside.

Figure 5 is a side elevation partly in section of the skull and upper jaw plate and also 40 the spring jaw, illustrating a slightly modified form of the invention.

Figure 6 is a cross section taken on the line 6—6 of Figure 5.

Figure 7 is a perspective view of the nose piece of the skull depicted in Figure 5.

45 Like numerals of reference indicate corresponding parts in each of the figures throughout the drawings.

In the drawings the reference numeral 10 generally denotes the skull which approximates in size and shape the head of the animal

to be mounted upon it. The skull is constructed of aluminum; either cast or pressed aluminum being adopted so as to produce a lightweight rigid skull.

11 denotes the nosepiece, 12 indicates an upper jaw plate constructed of wood and fitted to the underface of the skull, which jaw plate is of a greater width than the nose piece 11 and extends laterally on each side thereof as at 13. The rear portions 14 of this jaw plate have their edges 15 cut away or stepped so as to let the flange or lower edge 16 of the skull fit therein. This cut away portion is clearly shown in Figure 4 and is of a depth equal to the thickness of the flange 16 so that the outer surface of the flange will be flush with the adjoining plate edge. The skull is pierced in the vicinity of its lower edges in order to receive fastening elements 17 preferably consisting of nails as shown, which 20 nails are inserted in the openings in the skull and driven into the wooden jaw plate in order to securely attach it to the skull. 18 are 25 openings for receiving the wire that attaches the eyes. 19 is the customary lower jaw element one part 20 of which represents the lower jaw of the animal, while the other forms a lever 21 by which this jaw is opened against its spring pressure. The lever is pivoted to an attaching plate 22, which attaching plate is secured to the upper jaw plate by 30 inserting it through staples 23 driven into 35 said upper plate.

From the foregoing description it will be seen that this invention presents an exceedingly simple yet serviceable skull upon which a skin may be readily blocked. The jaw plate being of wood renders it quite convenient to tack the wet skin over the nosepiece 11 in order to hold it in shape until it 40 dries.

Referring to the modification shown in Figures 5, 6, and 7, this relates strictly to a pressed metal skull, the difference here being that the nosepiece 11 of this skull is provided with a pair of opposing integral lugs 24, 24' depending from the edges 25 and in approximately the same plane as the walls of the nosepiece. The ends of these lugs are inwardly curved as shown. The upper jaw 100

plate 12 is provided with an aperture 26 to receive these lugs. In the assembling of this modification, the upper jaw-plate is fitted to the skull with the lugs 24, 24' projecting through the aperture 26. The attaching plate 22 of the lower jaw element is then forced between the lugs in order to spread them in the aperture, which lugs owing to their tension not only secure the upper plate 10 to the skull but also attach the plate 22 at the same time, thus securely locking the three parts together without the use of any tools, see Figure 6. It will be noted that the lugs when spread have their curved ends 27 fitted 14 over the edges of the attaching plate 22 in such a manner as to firmly secure the same.

What I claim is:—

1. A skull of the class described comprising a hollow metal member approximating in size and shape the head of the animal that is to be mounted on it, and a wooden upper jaw plate secured to the metal member.
2. A skull of the class described comprising a hollow metal member approximating in size and shape the head of the animal that is to be mounted on it, a wooden upper jaw plate, and securing elements fastening the jaw plate to the metal member.
3. A skull of the class described comprising a hollow metal member approximating in size and shape the head of the animal to be mounted on it, a wooden upper jaw-plate having its opposing sides cut away to permit downwardly projecting portions of the skull to fit therein flush with the side edges thereof, and nails inserted in openings provided in said projecting portions of the skull and driven into said upper jaw-plate.
4. In combination, a pressed metal skull, a pair of integral lugs downwardly projecting from juxtaposed walls thereof and having inwardly curved ends, an upper jaw-plate having an aperture receiving said lugs, and an attaching plate of a lower jaw forced between the protruding ends of the lugs and gripped by their curved ends.

Signed at Toronto, Ontario, Canada, this 27th day of October, 1930.

CHARLES ABEL HOSIER.
